UNITED STATES PATENT OFFICE.

JOHN MURRAY, OF LONDON, ENGLAND.

MEANS FOR ROUNDING BOOKS.

Application filed October 7, 1925. Serial No. 60,989.

The present invention relates to improvements in means employed in effecting the operation in book-binding known as "rounding" and more particularly concerns improvements in machines such as described in the specification of my prior Patent No. 1,489,896 issued 8th April, 1924. In the machine described in the said prior specification there is provided a block having a slightly convex upper surface which feeds the books from a hopper to a position where they are seized by rounding rollers and rounded. For certain classes of work the arrangement referred to is satisfactory, but with other classes the rounding is not uniform and this want of uniformity of rounding results in irregularity of the succeeding operation, namely, the backing or jointing operation.

In accordance with a principal feature of the present invention, in lieu of an elevating block with a slightly convex upper surface—as described in my said prior specification—there is employed a convex former, which is preferably interchangeable to suit different thicknesses of books, and in association with this convex former there is provided a concave former, preferably formed in halves, which receives the back of the book, the rounding operation being effected by the convex former pushing the book to be rounded between guide plates until the back is forced into the concave former; the required rounding being imparted to the book by the action of the convex former on the fore-edge of the book and the action of the concave former on the back of the book. As a definite rounding is thus given to the book, and as the book is clamped after rounding and may be backed or jointed without change of position, it follows that the round and back or joint of the back of the book will be uniform and exact in size.

The concave former, which, as stated, is preferably formed in halves, is carried by cross-heads located one on each side of the guide plates, by which the book is guided in its movement into position. Such cross-heads are preferably suspended from the lower ends of links which are carried at their upper ends by crank arms mounted on transverse shafts. In a preferred arrangement the links are adapted to be actuated to move the crossheads and thus the halves of the former towards and away from one another i. e., towards and from "rounding"

position, in timed relation to the movement of the clamp by means of slotted links and rods connected thereto by turn-buckles permitting adjustment, such slotted links being adapted to be displaced through the medium of cams mounted, say, on one of the transverse shafts, to which shaft are attached crank arms connected by rods with the toggle serving to operate the clamp, as described in my prior specification, in such wise that the closing or opening of the clamp toggle is accompanied by movement of the crossheads to which the former is attached.

Suitably, portions of the mechanism by which the crossheads and thus the halves of the former are moved to and fro are located on the block to which the movable jaw of the clamp with its operating components, is attached, but the links supporting the cross-head remote from such movable jaw are supported on shafts carried on brackets mounted on a fixed part of the machine. Adjustment of the block when changing the machine for thicker or thinner books will automatically change the position of all the mechanism located on the block, but the half of the former on the crosshead remote from the block will be displaced from its proper relative position. There is provided therefore a mechanism by which the effective length of the rods actuating the crossheads may be varied and thus the position of the crossheads corrected. This correction or adjustment of the crossheads is conveniently effected by means of worm and spur gearing adapted to rotate the turn-buckles connecting the slotted links and the rods actuating the crossheads.

To adjust the distance between the tips of the gripping jaws of the clamp and the underside of the concave former at each side there are preferably provided brackets fitted with worms adapted to engage worm wheels keyed or otherwise secured to the shafts supporting the crossheads, so that on rotation of handles supported in the brackets the shafts may be rotated to cause the links, from which the crossheads are supported, to move upwards or downwards to raise or lower the concave former.

The invention is illustrated in the accompanying drawings in which Fig. 1 is an elevation and Fig. 2 a plan of mechanism devised to realize the aforescribed objects. Figs. 3 and 4 show details of the convex former.

In the drawings A denotes the block on which is mounted the movable jaw B of the book clamp constituted by such movable jaw and a stationary jaw E. H indicates the guide plates between which is guided the book N to be rounded, K, the convex former (shown in detail in Figs. 3 and 4) and M the concave former which in co-operation with the former K serves to round the book N.

Supported on brackets A1, A2, A3, A4 mounted on the block A, and on brackets A5, A6 to the left side of the rounding station (Figs. 1 and 2), are cross shafts A7, A8, A9, A10, A11, which are free to rotate in bearings in the brackets.

Fixed to the shafts A8 and A9 are crank arms or short levers A12, A13, A14, A15 carrying pins from which are suspended parallel links A20, A21, A22, A23. At their lower ends the links A20, A21, A22, A23 are attached to a cross head A24. A crosshead A25 is suspended in similar manner by links A20*, A21*, A22*, A23* from crank arms A12*, A13*, A14*, A15* fixed to the shafts A10 and A11. These crossheads A24 and A25 serve to support the concave former M which is formed in halves, each half being dovetailed to the relative crosshead A24 or A25, and being adapted to be retained in position by the flanges of screws A27, A28, engageable in recesses in the edges of the former M.

The right hand half (Fig. 1) of the former M is adapted to be actuated through the medium of slotted links B18, B19, connected by turn-buckles R2, R3 and rods B22, B23, to the links A20, A22. The left hand half of the former is adapted to be actuated in a similar manner through the medium of slotted links B20 and B21 connected by turn-buckles L2, L3 and rods B24, B25 to the links A20*, A22*.

With the arrangement provided it is possible to replace the concave former halves by former halves of different size, the screws A27, A28 being temporarily released. To suit the concave former adopted the convex former is adapted to be interchanged for which purpose the convex former is readily removable.

When the book has been formed or rounded, the clamp B, E is closed and grips the book N firmly enough to resist the pressure exercised thereon by the backing or jointing roller T, it being understood that before such roller can operate on the back of the book the concave former halves are withdrawn clear of the path of the roller. The mechanism for moving the roller in its arcuate path forms no part of the invention and may be the same as that described in my said prior patent for moving the roller therein designated B11.

To effect automatic withdrawal of the

former halves, there are employed cams B1, B2, B3, B4 fixed to the shaft A7 to the ends of which are fixed crank-arms B5 and B6 connected by rods B7 and B8 to the clamp toggle joint B9, which is actuated as described in my said prior specification. These cams B1, B2, B3, B4 are tracked by antifriction rollers B10, B11, B12, B13, B14, B15, B16, B17 attached to the links B18, B19, B20, B21. The oscillatory movement of the cams which occurs concomitantly with the movement of the arms B5, B6, thus effects movement of the former halves concomitantly with the opening and closing of the clamp. The parts E7, E6, E17, E8 and E9 constituting the principal parts of the former-actuating mechanism correspond to the parts denoted by the same reference characters in my said prior patent.

To avoid serious loss of time in changing the position of the foregoing components of the machine the adjustment should be facile and precise and this is arranged for as follows:—

Adjustment of the block A for change in thickness of the books will automatically change the position of all the right hand mechanism sustained thereby. As the left hand half of the former will be displaced from its position correction is provided for as follows:—The rotation of the hand lever L1, will rotate through the worm and spur gearing V, V1, V2, V3, V4, the turn-buckles L2, L3 to increase or diminish the effective length of the rods B24 and B25, and thus correct the position of the cross-head A25. Correction or adjustment of the position of the crosshead A24 and right hand half of the former may similarly be effected by rotation of the turn-buckles R2, R3 by worm gearing W, W1 operated by rotation of the hand lever R1.

A further important adjustment provided for is that of the distance between the tips of the clamp jaws and the under side of the concave former at J1, J2. Supported on the shafts A8, A9 is a bracket D1, on the underside of which is cut a recess in which are fitted worm wheels D4, D5 on to the shafts A8 and A9 by any suitable means. Supported in a boss on the upper side of the bracket D1 is a shaft D10 on which are cut worms D8, D9 which mesh with the worm wheels D4, D5. Cut on the shaft D10 is also a small worm wheel D11. Above the worm wheel D11 and supported in a boss is a worm D14 fixed to the shaft D12 rotatable by the hand lever D13. As will be evident, the rotation of the hand-lever D13 will rotate the shafts A8, A9 and thereby the crank-arms A12, A13, A14, A15 to raise or lower the right hand half of the former according to the direction of rotation. Similar means are provided, as shown, for raising or lowering the left hand half of the former.

- The convex former K, as shown in detail in Figs. 3 and 4, is attached by means of pins K1, K2, fitted in key-hole slots K3, K4, on the under side of the former K.
- 5 The pins K1 and K2 are fixed to a block K5, which may be rigidly mounted, or, as shown, may be resiliently mounted on spring-supported pins K9 and K10 on the elevator arm K6.
- 10 Strips K7 attached to the former and extending downwards to the books in the hopper serve to prevent them from being caught by the former on its downward movement.
- 15 A spring K11 maintains the hemispherical head of a pin K12 in a slight depression in the former K, and by this means the former is retained in its position during the operation of the machine. The retaining force is,
- 20 however, easily overcome by a pull on the former when removal is desired.
- The limiting position of the block K5, on which the position of the former K depends, depends in turn on the limiting position of 25 the pins K9 and K10.
- The parts H1, H2, H4, H5, H8, H9, H11, H12, H13, H14, H15 and G12 of the mechanism for actuating the convex former K correspond to the similarly designated parts described in my said prior patent, in the paragraph beginning with line 126 of page 3.
- What I claim is:—
1. Means for mechanically rounding books, comprising a fixed frame, a block 35 adjustable in relation to said fixed frame, a book clamp including a stationary jaw sustained by said fixed frame and a movable jaw slidable in relation to said block, a concave former comprising halves, one half above each jaw of said clamp, said former adapted to receive the back of the book to be rounded, a carrier sustained by said fixed frame, a carrier sustained by said block, a set of elements sustained by said first named carrier by which one half of said former is supported, a set of elements sustained by said second carrier by which the other half of said former is supported, an actuator, 40 separate connections between said actuator and said sets of elements for communicating to said former halves movements towards and from one another, means for relatively adjusting said connections to correspond with adjustment of said block, connections between said actuator and said movable jaw, a convex former adapted to engage the fore-edge of the book and to press the back of the book into said concave former, and connections between said actuator and said convex former.
- 45 2. Means for mechanically rounding books, comprising a fixed frame, a block adjustable in relation to said fixed frame, a book clamp including a stationary jaw sustained by said fixed frame and a movable jaw slidable in relation to said block, a concave former comprising halves, one half above each jaw of 50 said clamp, said concave former adapted to receive the back of the book to be rounded, a pair of crossheads, each former half removably fitted to a crosshead, a set of links having a support on said frame by which 55
- able in relation to said block, a concave former comprising halves, one half above each jaw of said clamp, said former adapted to receive the back of the book to be rounded, guide plates between which the book is 70 guided in its movement into rounding position, crossheads located one on each side of said guide plates, each crosshead carrying one half of said former, shafts carried by said block, a set of links connected to said shafts by which one crosshead is suspended, shafts carried by said fixed frame, a set of links connected to said second named shafts by which the other crosshead is suspended, an actuator, separate connections between 75 said actuator and said sets of links for communicating to said crossheads movements towards and from one another, means for relatively adjusting said connections to correspond with adjustment of said block, connections between said actuator and said movable jaw, a convex former adapted to engage the fore-edge of the book and to press the back of the book into said concave former, and connections between said actuator and said 80 convex former.
3. Means for mechanically rounding books, comprising a fixed frame, a block adjustable in relation to said fixed frame, a book clamp including a stationary jaw sustained by said fixed frame and a movable jaw slidable in relation to said block, a concave former comprising halves, one half above each jaw of said clamp, said former adapted to receive the back of the book to be rounded, means 95 for effecting vertical adjustment of said former halves, a set of links having a support on said frame by which one half of said former is suspended, a set of links having a support on said block by which the other half of said former is suspended, an actuator, separate sets of connections between said actuator and said sets of links for communicating to said former halves movements towards and from one another, means 100 for adjusting one set of said sets of connections to compensate for adjustment of said block, connections between said actuator and said movable jaw, a convex former adapted to engage the fore-edge of the book and to 105 press the back of the book into said concave former, and connections between said actuator and said convex former.
4. Means for mechanically rounding books, comprising a fixed frame, a block adjustable 110 in relation to said fixed frame, a book clamp including a stationary jaw sustained by said fixed frame and a movable jaw slidable in relation to said block, a concave former comprising halves, one half above each jaw of 115 said clamp, said concave former adapted to receive the back of the book to be rounded, a pair of crossheads, each former half removably fitted to a crosshead, a set of links having a support on said frame by which 120
